UNITED STATES PATENT OFFICE

109,674

DESIGN FOR A STOOL

Joseph M. Ranko, New York, N. Y.

Application February 8, 1938, Serial No. 74,965

Term of patent 7 years

To all whom it may concern:

Be it known that I, Joseph M. Ranko, a citizen of the United States and residing at New York, in the county of New York, and State of New York, have invented a new, original, and ornamental Design for a Stool, of which the following is a specification, reference being had to the accompanying drawing, forming part thereof.

Fig. 1 is a perspective view of the stool, showing my design; and Fig. 2 is a horizontal sectional view taken on line 2—2 of Fig. 1.

I claim:

The ornamental design for a stool as shown.

JOSEPH M. RANKO.
